WILLIAM F. BOUCHÉ, OF DEPEW, NEW YORK, ASSIGNOR TO GOULD COUPLER COMPANY,
A CORPORATION OF NEW YORK.

MEANS FOR DRIVING DYNAMOS FROM CAR-AXLES.

1,145,465.

Specification of Letters Patent.

Patented July 6, 1915.

Application filed January 30, 1914. Serial No. 815,342.

To all whom it may concern:

Be it known that I, WILLIAM F. BOUCHÉ, a citizen of the United States, and a resident of Depew, county of Erie, State of New York, have invented certain new and useful Improvements in Means for Driving Dynamos from Car-Axles, of which the following is a specification.

My invention relates to improvements in means whereby dynamo electric machines may be efficiently driven from the axle of railway cars or the like. Many arrangements have been suggested for the driving of dynamos from car axles and the so-called shaft-drive has several advantages over the so-called belt-drive, especially in that the dynamo may be rigidly supported from the car body which is cushioned on the trucks so that the dynamo is not subjected to the heavy jolts and jars to which the trucks are subjected. Also the positiveness of action and avoidance of belt breakage are advantages of the shaft drive. In the shaft-drive arrangements, however, where it has been proposed to place a bevel gear upon a car axle and drive from this a bevel gear on a shaft at right angles to the axle, certain disadvantages have arisen, in that, to get the necessary reduction in gears, the second bevel gear has been so small with respect to the first bevel gear that the parts are subject to very great wear and tear and are apt to soon become loose and get out of order. Also generally, due to wear, there is a certain relative lateral movement between the gears which causes a looseness of parts, great wear and tear and a change of the relative speeds of the gears.

The main object of my invention is to overcome these disadvantages and provide a shaft-driven arrangement which is efficient and economical in operation and construction and supported in a simple and efficient manner.

Further objects, advantages and features will more clearly appear from the detailed description given below taken in connection with the accompanying drawings which form a part of this specification and illustrate my improvements in a preferred form.

I desire it to be understood, however, that many changes, modifications and omissions may well be made without departing from the spirit and scope of my invention in its broader aspects, and accordingly I do not

desire to be limited to the details shown and described except as clearly specified in the appended claims.

In the drawings, Figure 1 shows a side elevation of the arrangement applied to a car; Fig. 2 is a vertical section through the driving gearing; Fig. 3 is a plan of the same partly in section; and Fig. 4 is an end view of the parts shown in Fig. 3, partly in section.

Referring to the drawings, 1 represents the body of a railway car provided at one end with a truck 2 having end sills 3 supported by the axle 4 carrying the usual wheels 5. Secured to the body of the car 60 is a framework 6 rigidly carrying a dynamo electric machine 7 having an armature adapted to be driven by a short shaft 9 adapted to slide in bearings 10 in the direction of its axis, which bearings are rigid 65 with the framework of the motor. The shaft 9 carries a pin 11 adapted to engage a resilient metallic member 12 projecting from a disk 13 carried rigid with the rotating armature of the dynamo, which member 12 is adapted to give way or break in case the dynamo should become stopped for any reason while the car is still running, and thus prevent breakage of the shafting or other parts.

Rigidly secured to the axle 4 is a flat faced gear 14 meshing with a smaller flat faced gear 15 carried on a countershaft 16 having bearings rigid with the casing 17, which casing surrounds the gearing and is adapted 70 to contain oil or grease for lubricating the parts in a well known manner. The casing 17 is at one end supported by the axle 4, the axle 4 running in bearings 18 therein, which bearings have a bushing of cast brass 19 lined with a bearing 20 of Babbitt metal. The countershaft 16 is provided with similar bearings at 21. The bearings 18 are provided with oil or grease apertures 22 through which oil or grease is supplied from 75 the casing 17 into the bearings 18.

At one end the countershaft 16 is supported by ball bearings 23, and adjacent these bearings there is secured to the countershaft a bevel gear 24 meshing with a smaller bevel gear 25 secured to a short shaft 26 running in roller bearings 27 carried rigid with the head 28 forming part of the casing 17. The head 28 forming the outer end of the casing 17 is supported from 80 105 110

the end sill 3 by means of a link 29 pivoted to an arm 30 extending from the sill 3 and a link 31 pivoted to the head 28 with an intervening link 32 connecting these two links 29 and 31 and pivoted thereto at right angles to the pivots by which they are connected to the arm 30 and head 28, respectively. The short shaft 26 is connected to intermediate shafting 33 by means of a universal joint 34 and the shafting 33 is connected to the short shaft 9 by means of a universal joint 35. By thus providing a plurality of sets of reducing gears the gears 14 and 15 may be made more nearly of the same size and the gears 24 and 25 may be made more nearly of the same size so that there is less wear and tear of them and they are less likely to get out of order. Also, by providing the intermediate gear 15 running on a countershaft parallel with the axle the casing may be permitted to slide slightly along the axle without in any way affecting the meshing of the gears 14 and 15, so that if the parts become worn so as to permit this slight shifting, there is no danger of the gears 14 and 15 binding or getting out of order. Also, by suspending the outer end of the casing from the sill 3 by means of the pivotal link connection 29, 32, 31, all strain is relieved from the parts and the casing with its contained gearing is supported so that it will hang freely and is not likely to get out of order. At the same time the arrangement is simple and efficient in construction and the parts are easily replaced.

By providing a shaft 33, having a universal connection with the driving shaft 26, and a universal connection with the dynamo shaft, the shaft 33, by means of the shaft 9, having a sliding movement with respect to the dynamo shaft, relative vertical and lateral movements between the dynamo and axle, due to the swinging of the truck and the vertical movement of the car body on its springs, are provided for.

Having fully and clearly described my improvements, what I claim as new and desire to secure by Letters Patent, is:

1. An apparatus of the class described, having in combination with a railway car body, its truck with sills and axles, a dynamo supported rigidly from the car body and adapted to be driven from an axle of the car, driving means connecting the axle with the dynamo electric machine comprising a countershaft parallel with the axle, a gear on the axle, a smaller gear on the countershaft meshing therewith, a driving shaft at right angles to the axle, a beveled gear on the countershaft, a smaller beveled gear on the driving shaft meshing with said first mentioned beveled gear and a shaft having a universal connection with said driving shaft and a universal connection with the dynamo shaft, one of said last mentioned

three shafts having a sliding movement with respect to another one of them, whereby relative vertical and lateral movements between the dynamo and axle are provided for.

2. An apparatus of the class described, having in combination with a railway car body, its truck with sills and axles, a dynamo supported rigidly from the car body and adapted to be driven from an axle of the car, driving means connecting the axle with the dynamo electric machine comprising a countershaft, a gear on the axle, a gear on the countershaft meshing therewith, a driving shaft, another gear on the countershaft, a gear on the driving shaft meshing with the second gear on the countershaft and a shaft having a universal connection with said driving shaft and a universal connection with the dynamo shaft, one of said last mentioned three shafts having a sliding movement with respect to another one of them, whereby relative vertical and lateral movements between the dynamo and axle are provided for.

3. An apparatus of the class described, having in combination with a railway car body, its truck with sills and axles, a dynamo supported rigidly from the car body and adapted to be driven from an axle of the car, driving means connecting the axle with the dynamo electric machine comprising shafting having mechanical connections with the dynamo electric machine and gearing connecting the axle with said shafting, a casing for said gearing, said casing having a bearing for one end of the shafting, and a flexible connection for supporting said casing from one of the truck sills, said shafting comprising a driving shaft geared to the axle, and a shaft having a universal connection with said driving shaft and a universal connection with the dynamo shaft, one of said last mentioned three shafts having a sliding movement with respect to another one of them, whereby relative vertical and lateral movements between the dynamo and axle are provided for.

4. An apparatus of the class described, having in combination with a railway car body, its truck with sills and axles, a dynamo supported rigidly from the car body and adapted to be driven from an axle of the car, driving means connecting the axle with the dynamo electric machine comprising shafting having mechanical connections with the dynamo electric machine and gearing connecting the axle with said shafting, said gearing comprising a counter-shaft, a gear on the axle, a gear on the countershaft meshing therewith, a gear on the countershaft and a gear on said shafting meshing with the last mentioned gear, a bearing for one end of the shafting near the axle, and a flexible connection for supporting said bearing from one of the truck sills, said flexible

connection comprising a plurality of pivotally connected link members.

5. An apparatus of the class described, having in combination with a railway car body, its truck with sills and axles, a dynamo supported rigidly from the car body and adapted to be driven from an axle of the car, driving means connecting the axle with the dynamo electric machine comprising shafting having mechanical connections with the dynamo electric machine and gearing connecting the axle with said shafting, said gearing comprising a countershaft parallel with the axle, a gear on the axle, a smaller gear on the countershaft meshing therewith, a beveled gear on the countershaft and a smaller beveled gear on said shafting meshing with the first beveled gear, a bearing for one end of the shafting near the axle, and a flexible connection for supporting said bearing from one of the truck sills.

6. An apparatus of the class described, having in combination with a railway car body, its truck with sills and axles, a dynamo supported rigidly from the car body and adapted to be driven from an axle of the car, driving means connecting the axle with the dynamo electric machine comprising a countershaft, a gear on the axle, a gear on the countershaft meshing therewith, a driving shaft, means for mechanically connecting said last mentioned shaft with the dynamo electric machine, another gear on the countershaft and a gear on the last mentioned shaft meshing with the second gear on the countershaft, said mechanically connecting means comprising a part adapted to give way or break in case the dynamo should become stopped for any reason while the car is still running.

7. An apparatus of the class described, having in combination with a railway car body, its truck with sills and axles, a dynamo supported rigidly from the car body and adapted to be driven from an axle of the car, driving means connecting the axle with

the dynamo electric machine comprising a countershaft parallel with the axle, a gear on the axle, a smaller gear on the countershaft meshing therewith, a driving shaft at right angles to the axle, means for mechanically connecting said last mentioned shaft with the dynamo electric machine, a beveled gear on the countershaft, and a smaller beveled gear on the last mentioned shaft meshing with said first mentioned beveled gear, said mechanically connecting means comprising a part adapted to give way or break in case the dynamo should become stopped for any reason while the car is still running.

8. An apparatus of the class described, having in combination with a railway car body, its truck with sills and axles, a dynamo supported rigidly from the car body and adapted to be driven from an axle of the car, driving means connecting the axle with the dynamo electric machine comprising shafting having mechanical connections with the dynamo electric machine and gearing connecting the axle with said shafting, said gearing comprising a countershaft parallel with the axle, a gear on the axle, a smaller gear on the countershaft meshing therewith, a beveled gear on the countershaft and a smaller beveled gear on said shafting meshing with the first beveled gear, a bearing for one end of the shafting near the axle, and a flexible connection for supporting said bearing from one of the truck sills, said mechanically connecting means comprising a part adapted to give way or break in case the dynamo should become stopped for any reason while the car is still running.

In testimony whereof, I have signed my name to this specification, in the presence of two subscribing witnesses.

WILLIAM F. BOUCHE.
